CLOSURE FOR BOTTLES, JARS, AND
SIMILAR CONTAINERS

Charles D. Magnesen and Hooker Magnesen,
Chicago, Ill., assignors to The Magnesen Seal
and Closure Company, Chicago, Ill., a corpo-
ration of Illinois

Application July 31, 1933, Serial No. 682,920

5 Claims. (Cl. 215—45)

Our invention relates to a closure or cap adapted to effectively close and seal the mouths of bottles, jars, metal cans or other containers and which may readily be applied and removed by hand as many times as desired. The principal object of our invention is to attain a high and uniform degree of effectiveness in closing and sealing the bottles or other containers, notwithstanding some irregularity in forming the neck 5 openings to be sealed, and other objects are to provide a simple and inexpensive cap which can be cheaply manufactured and which can be applied and removed easily by manual operation a great number of times without becoming distorted or losing its effectiveness, and which in general shall be better adapted to serve the purposes for which it is designed than other bottle caps known to us. The invention provides a closure having a constant downward pulling tendency 10 making it an effective seal for ordinary purposes. It has the additional advantage, however, of permitting the escape of excessive internal pressure by moving to a slightly open position. When the internal pressure has again become normal the 15 construction of the fingers is such that the constant downward tension of the fingers will reseat the closure in its normal position. To these ends we have designed and invented the novel bottle and jar closure hereinafter described in detail, 20 the essential elements of our invention being more particularly pointed out in the appended claims.

Of the drawing, Figure 1 shows a top plan view of our invention in a preferred form; Fig. 2 is a central vertical section of the same, certain 25 parts being broken away and other parts shown in elevation to better illustrate its construction; Fig. 3 is a fragmentary portion of a central section of a modified form of closure; Figs. 4 and 5 are similar fragmentary sections of two other 30 forms; Fig. 6 is a fragmentary side elevation showing a modified form of the marginal fingers of the inner closure member; and Fig. 7 is a fragmentary bottom plan view of a further modified form of my invention.

45 Like reference characters indicate the same parts in all the figures of the drawing.

Describing first the construction illustrated in Figs. 1 and 2, the closure consists of two principal sheet metal members and one auxiliary member, 50 in addition to the usual compressible gasket, or "liner", of cork, or other suitable equivalent material, the closure being in this instance shown applied to the top or neck of a container such as a metal oil or varnish can. This neck is formed 55 with an external annular channel 2 a short dis-

tance below the top of the neck, which may be recurved inwardly at 3 around the neck opening for the purpose of providing greater strength and regularity of surface at the seating or sealing face of the closure.

The inner member of the closure is a generally cup-shaped member 4, the central portion of the top of which may be domed as shown, the domed portion 5 being surrounded by an annular plane portion 6 in alignment with the seating face or edge 3 of the neck 1 of the container. Within the member 4 is arranged the auxiliary metal member 7 preferably formed with a narrow flange 8 arranged to receive the liner 9, which, when the closure is applied, bears directly on the top 15 face of the neck of the container.

Outside the annular portion 6 of the member 4 the metal of the member is bent downwardly around the top of the auxiliary member 7, and connected to this downwardly bent portion is a 20 series of narrow fingers 10 which collectively form a divided downwardly extending skirt. Intermediate their length these fingers are formed with transverse bends 11 and the ends of the fingers are formed with inward rolls 12, of substantial 25 size and having free ends arranged to engage and cooperate resiliently with the overhanging engaging face provided by the upper portion of the channel 2 of the neck of the container.

The outer member of the closure is an annular 30 member 13 formed with a skirt 14 having an external bead or flange 15 at its lower edge for imparting strength and providing a convenient finger grip for manipulating the cap in applying and removing it.

In applying the closure the inner member 4, with the auxiliary member 7 and liner 9 assembled therein are slipped over the neck of the container, the fingers 10 yielding sufficiently to permit the rolls 12 to pass into the groove of the neck 40 and make elastic engagement with it, and the outer member 13 is then forced downward over the inner member, the inner face of the skirt of the outer member bearing against and slightly pressing inwardly the fingers at their bends 11 45 and then bearing against the outer side of the rolls 12 as it comes opposite them, with the result that the inner member is frictionally stressed downward, and through the inherent elasticity of the rolls and their camming action against the upper face of the groove the fingers are drawn downward with a yielding pull. The metal of which the inner member is formed possesses some degree of elasticity, and it will be noted 50 that the rolls 12 cooperate at their free inner 55

ends with the overhanging portion of the groove or channel 2, from which, (in connection with the bends 11) it results that the fingers exhibit a considerable degree of longitudinal elasticity 5 with reference to tensional strains in the direction of their length. This longitudinal elasticity exhibited by the fingers produces a yielding stress exerted around the margin of the inner or closure member tending to draw it downwardly on the 10 container top. To attain greater resiliency in the fingers, they may be given a double bend, as illustrated in the sinuous bend 16 in Fig. 4, or may have zig-zag corrugations, as shown in Fig. 5, where the corrugated portion is marked 17. 15 Furthermore, it will be noted that the central flat portion of the inner member 7 extends some little distance radially beyond or outside the edge of the sealing face of the container top, from which it results that the yielding pull of the 20 several fingers around their point of connection with the central portion mentioned enables it to "weave" or flex slightly to adjust itself to slight irregularities in the edge of the container top, and this contributes to an effective sealing of the 25 container.

While the outer member may conveniently be formed of sheet metal of the same character as that used for the inner member, it need have no 30 resilient or elastic qualities, and may be made of any other strong, stiff material.

For the purpose of positively locking the inner and outer members of the closure together, a diametrically opposite pair of lugs 18 (shown in different positions in full and dotted lines) are 35 struck up from the top of the inner member 4 which may be bent outwardly over the inner edge of the outer member, as shown in full lines. These may be used for greater security in shipment or handling filled containers, but ordinarily need 40 not be employed.

For the purpose of preventing undetected substitution of the contents of a container, these lugs are so constructed that the closure cannot be removed from the container without rebending 45 the lugs into a perpendicular position, the lugs then having a tendency to break off. It will be noted, however, that in the event such lugs are broken off the efficiency of the closure for reuse is not thereby impaired, due to the additional or 50 auxiliary top member 7 in Figure 2 which auxiliary top member is not disclosed in other figures.

In Figs. 3, 4, and 5 forms of our novel closure are shown applied to glass or stone bottles or 55 jars formed with overhanging engaging faces or surfaces adapted to cooperate with the rolls 12 of the inner member in the same manner as the groove 2 of the closure shown in Fig. 2. In the container of Fig. 3 the top of the container is 60 formed with a square shoulder 19; in that of Fig. 4 with an angular beveled shoulder 20; and in Fig. 5 the top 21 of the container is formed with an outwardly flared or funnel-shaped face.

In the closure illustrated in Fig. 3 the inner 65 member, marked 22, is not perforated to provide lugs such as the lugs 18 shown in Fig. 2, and consequently an auxiliary metal member, such as the member 7 above mentioned is not necessary. The flexible margin of the inner member 22 in 70 this form of our invention, projecting radially beyond the seating face of the container cap, is of course free to weave or flex slightly and thus adjust itself to the seating edge of the container top, notwithstanding some irregularity in the 75 container top, in the same manner as the mar-

ginal portion of the member 7 in the form of our invention previously described.

In the form of our invention shown in Fig. 3, moreover, the top of the member 22 is but slightly dished, so that it may be sprung, with an 5 elastic snap action, from the extreme upper position shown, to an extreme opposite lower position in which the peripheral upper portion of the cap will flare slightly upwardly, with the effect of spreading the ends of the row of fingers outwardly, thus facilitating its application to the bottle neck. When the outer member is then applied and forced downwardly so as to press the fingers inwardly it will automatically cause the central portion of the top to snap outwardly 15 again.

Preferably the portion of the fingers of the inner closure members which form the rolls 12 should be somewhat narrower than the upper portions, to avoid undue stiffness, which may be 20 attained by shouldering the fingers at the inner end of the roll portion as shown in Fig. 2, or the fingers may be uniformly tapered, as in the fingers 23, illustrated in Fig. 6.

In certain cases, as where a relatively thin 25 metal is used and it is desired to increase the stiffness of action, the rolls at the ends of the fingers may have a double curvature, as shown in Fig. 7, where the rolls, marked 24, are of the same length as the full width of the fingers, and each roll has 30 an axial curvature upon a radius less than the radius of the group of fingers.

It will be noted that the full closing and clamping effect of the outer member on the inner member is attained as soon as the lower edge of the 35 former touches the maximum diameter of the rolls at the ends of the fingers of the inner member, and extreme accuracy in forcing the outer member down to the limit of its movement is not necessary.

In practice it has been found that the elasticity of the many rolls and fingers is such that the cap will make a perfect closure at the sealing face of the top of the container, notwithstanding a considerable irregularity in the contour of such face, 45 or variations in the thickness of the gaskets used; and furthermore, while the cap will withstand a very high degree of internal pressure, it will, in case of excessively high pressure, yield and then reseat itself when the excess pressure has escaped. 50 Moreover, since the sealing action is largely due to the elastic action of parts which are spaced somewhat away from the neck opening, and there is no large unbroken field of frictional contact of the members which might be cemented together 55 by portions of the contents of the container, there is very little liability for the parts to "freeze" or stick together, as is the case with many closures used for containers such as those above mentioned.

We are aware that bottle closures of the general type known are shown in the art, but so far as we are aware, none of them are so constructed as to exhibit effective longitudinal elastic stress upon the finger members, which in in applicants' device 65 is attained and contributed to in varying measure by the cylindriform open end rolls of the narrow fingers, the transverse bends of such fingers, the bearing of the outer member of the closure upon the outer face of the transverse 70 bends, and the flexible extended margin of the inner closure member extending beyond the seating face of the container top.

While in the various forms of our invention above described we have made mention of the 75

outer, or locking member as an essential part of the complete device, it will be understood that in some cases a portion of the advantages of our invention may be realized by using only the inner 5 member of the device, and we regard such construction as within the scope of certain of the claims hereinafter set forth. In case of the use of our invention in such form we contemplate shortening the length of the fingers by carrying 10 the cuts defining them to a level only a short distance above the upper side of the rolls, or by making the members of relatively stiff and strong material, so that the rolls will exhibit sufficient strength and stress to effect efficient sealing.

15 We claim:

1. A closure comprising a top member adapted to cover the opening of a receptacle, a plurality of relatively-narrow longitudinally-yielding fingers originating at and depending from said top member about the periphery thereof, each finger being formed with an outward resilient horizontal corrugation intermediate its ends and with an inwardly-curved resilient terminal portion, and an outer member contacting the outward bulges of the fingers, whereby the outer member subjects said fingers to pressure occasioning longitudinal extension of said fingers to thereby compensate for irregularities on the underside of the shoulder of a receptacle to which said fingers may be applied.
2. A closure comprising a top member larger than and adapted to cover the opening of a receptacle, a plurality of longitudinally-yielding fingers originating at and depending from said top member about the periphery thereof, each finger being formed with resilient outward bends intermediate its ends and with an inwardly curved resilient portion at its lower end, and an outer member frictionally contacting the outward bends of the fingers, whereby said outer member subjects the fingers to pressure occasioning longitudinal extension thereof while maintaining the lower ends of the fingers in contact with the receptacle.
3. A closure comprising a top member adapted to cover the opening of a receptacle, a plurality of

relatively-narrow longitudinally-yielding fingers originating at and depending therefrom, said fingers having resilient horizontally corrugated portions intermediate their ends and inwardly curled open rolls at their free ends, and a retaining member telescoped over said first-mentioned member contacting the horizontal corrugated portions of the fingers but otherwise spaced therefrom, whereby the retaining member effectuates a tight yielding seal between the top member and the 10 mouth of the receptacle to which said closure may be applied.

4. A closure comprising a top member adapted to cover the opening of a receptacle, a plurality of relatively narrow longitudinally-yielding fingers originating at and depending therefrom, said fingers having resilient transverse outward beads intermediate their ends and inwardly curled open rolls at their free ends, and a retaining member telescoped over said first-mentioned member contacting said beads on the fingers, but otherwise spaced therefrom, whereby the pressure of the retaining member effectuates longitudinal extension of the fingers and produces a tight yielding seal between the top member and the mouth of 20 the receptacle to which said closure may be applied.

5. A closure comprising a top member larger than and adapted to cover the opening of a receptacle, a plurality of longitudinally-yielding fingers originating at and depending from said top member about the periphery thereof, each finger being formed with a resilient bend or bends intermediate its ends and with an inwardly-curved resilient portion at its lower end, an outer member frictionally contacting the outward bends of the fingers, whereby said outer member subjects the fingers to pressure occasioning longitudinal extension thereof while maintaining the lower ends of the fingers in contact with the receptacle, 40 and destructive means connecting the top member and the retaining member to prevent undetected substitution of the contents of a receptacle on which the closure is applied.

CHARLES D. MAGNESEN. 45
